UNITED STATES PATENT OFFICE.

RAY P. DEARDORFF, OF BUFFALO, NEW YORK.

ARC-LAMP REGULATION FOR HEADLIGHTS.

1,268,548.

Specification of Letters Patent. Patented June 4, 1918.

Application filed December 2, 1913. Serial No. 804,236.

To all whom it may concern:

Be it known that I, RAY P. DEARDORFF, a citizen of the United States, residing at Buffalo, Erie county, New York, have invented certain new and useful Improvements in Arc-Lamp Regulations for Headlights, of which the following is a specification.

This invention relates to arc lamps generally, and more particularly to an arc lamp that is suitable for use on locomotives or other vehicles where an arc headlight is desired.

One of the objects of the invention is to provide the arc lamp with a novel automatic regulating mechanism which will maintain the electrodes in a predetermined position at all times when the current is turned on and afford a very close regulation of the same.

Another object of the invention is to arrange the apparatus in a compact form on a suitable base so that the entire arc interior of the lamp may be readily removed from its casing for repairs or adjustment and replaced without otherwise disassembling the headlight.

Another object of the invention is to provide a novel mechanism for automatically feeding the electrodes as they waste away and as the voltage between the electrodes increases.

Another object of the invention is to provide an electric motor for driving the arc feeding mechanism, the said electric motor being provided with a differentially wound field coil and a suitable stop device to prevent its rotation in an improper direction.

The above, and other objects and the novel features of the invention will be apparent from the following description, taken in connection with the drawings, in which:

Figure 1 is a side elevation of the arc lamp, parts being broken away.

Fig. 2 is a plan view of the same, the reflector being shown in section.

Fig. 3 is a rear elevation of the same.

Fig. 4 is a detail sectional view on the line 4—4 of Fig. 2, looking in the direction of the arrows.

Fig. 5 is a diagram of the connections.

Fig. 6 is a detail sectional view, substantially on the line α — α of Fig. 3.

Referring to the drawings, the numeral 10 designates a suitable base of insulating material such as wood or the like upon which the arc lamp is mounted. At opposite ends of the base 10 I provide the brackets 11 and 12, which are permanently secured to the base 10. Each of the brackets 11 and 12 extends across the base and is provided at its ends with bearings 13. The bearings in the corresponding ends of the brackets 11 and 12 carry rods 14 and 15 which are parallel to each other and extend longitudinally of the base. Yokes 16 and 17 are apertured to receive the ends of the rods 14 and 15 beyond the brackets 11 and 12. The rods 14 and 15 are circular in cross section, and the yokes 16 and 17 slidably fit the ends thereof, having the downwardly extending portions 18 at opposite ends which are bored to receive the rods 14 and 15.

The yokes 16 and 17 are provided at opposite ends and above the projections 18 with lugs 19 which are drilled to receive the opposite ends of the guide rods 20 and 21, which are secured in the recesses in the lugs 19. The guide rods 20 and 21 are disposed directly over and parallel to the rods 14 and 15, and together with the yokes 16 and 17 form a rigid slideable frame carrying the arc apparatus, since the yokes 16 and 17 are longitudinally slideable for a slight distance at the outer ends of the rods 14 and 15.

The positive carbon electrode 22 is supported in a clamp 23 adjustable by means of the thumb screw 24 and formed integral with the standard 25. The base 26 of the standard 25 is secured to a yoke 27 and suitably insulated therefrom by the mica 28 or other suitable insulation. Extending laterally from the yoke 27 there are two arms 29 and 30, the arm 29 being formed with an elongated cylindrical portion 31, which embraces the rod 21 and is guided thereby. The arm 30 is forked at its end and the forked portion contacts with the upper and lower edge of the circular guide rod 20. Formed integral with the under side of the plate 27 is a threaded nut 32 which is adapt-

ed to receive and engage the threads 33 of the feed screw 34. The rotation of the feed screw 34 in a clockwise direction will feed the standard 25 toward the left in Fig. 1. The cylindrical portion 31 of the arm 29 and the forked arm 30 serve to guide the standard and maintain the electrode carried thereby in line with the negative electrode 35.

10 The negative electrode 35 is carried by the carbon holder 36 which is provided with a knurled locking nut 37. The carbon holder 36 is slidably supported in a sleeve 38 formed integral with and at the upper end 15 of the supporting standard 39. The carbon holder 36 extends through the sleeve 38, and a U-shaped armature 40 is rigidly secured to the rear end thereof. A leaf spring 41 secured at its lower end and mounted on 20 the supporting standard 39 has the upper end thereof pressing against the rear end of the carbon holder 36 and armature 40, yielding 25ingly keeping the carbon holder 36, armature 40, and electrode 35 at the extreme position of their forward and outward movements.

The armature 40 constitutes the armature for the bipolar starting magnet comprising the coils 42 and 43 secured to the cross 30 bar 44 which is attached to a ledge 45 on the supporting standard 39. The spring 41 is secured to said cross bar 44 by the screw 411. The coils 42 and 43 are wound on the cores 421 and 431 respectively, the 35 said cores extending upwardly beyond the coils and having adjustable faces 422 and 432, respectively disposed opposite the lower ends of the U-shaped armature 40. When the current is turned on to the arc lamp the 40 coils 42 and 43 are simultaneously energized and being substantially of the same strength will pull the armature 40 and carbon holders 36 with the carbon 35 attached thereto and strike the arc between the carbon elec- 45 trodes 22 and 35.

The supporting standard 39 is secured at its base 46 to a yoke 47, being insulated from the latter by the insulation 48. The yoke 47 is substantially similar to the yoke 27 50 on which the standard 25 is mounted. However, the cylindrical portion 49 of the yoke 47 fits the guide rod 20, whereas the forked arm 50 thereof fits the guide rod 21. This arrangement is simply the reverse of the 55 arrangement of the arms of the yoke 27 so as to secure a more perfect alinement of the electrodes. The yoke 47 is also provided with an internally threaded integral nut 51 on its under side, the nut 51 being threaded 60 to take the threads 52 at the left end of the feed screw 34. The threads 33 are right hand threads and are formed twelve to the inch, while the threads 52 are left hand threads and formed fourteen threads to the 65 inch. Consequently, the rotation of the feed

screw 34 will move the standards 25 and 39, and the electrodes 22 and 35 carried thereby toward each other. The positive electrode 22 which wastes away the more rapidly will, therefore, be fed and move more rapidly 70 than the negative electrode 35.

The feed screw 34 is journaled at one end in a boss 54 at the longitudinal center of the yoke 17, and has a wheel 55 secured at the outer end thereof by means of the set 75 screw 56. The wheel 55 has a series of ratchet teeth 57 on its periphery, which ratchet teeth are adapted to be engaged by a pawl 58 pivotally mounted at the outer end of a connecting rod 59. The pawl 58 and the connecting rod 59 are pivotally connected together by means of the screw 581 which has threaded engagement with the upper end of a plate 582 loosely supported on a smooth portion of the operating screw 34 and at the inner side of the wheel 55. The opposite end of the connecting rod 59 is provided with a strap 60 which fits an eccentric 61 formed integral with one side of the gear wheel 62. The gear wheel 62 is loosely mounted on a stub shaft 63 formed at the lower end of a bracket 64 secured to the motor frame 65. The outer end of the shaft 63 is screw threaded to receive the keeper plate 641 having internal threads 95 and arranged to maintain the eccentric strap 60 on the connecting rod 59 in proper relation to the eccentric 61 on the gear wheel 62. A laterally extending part 66 of the yoke 12 forms a platform for supporting 100 an electric motor M for driving the gear 62, the armature shaft of the motor having a pinion 67 secured thereto which meshes with the gear wheel 62, as shown in Fig. 3.

The frame 65 of the motor has the pole 105 shoes secured to opposite sides thereof. The pole shoes 68 are also secured to the core of a differentially wound field magnet 69. The positive and negative brushes of the motor are mounted in a suitable brush 110 holder yoke 70. In order to prevent the motor from driving the gear wheel 62 at certain times in the operation of the apparatus and in order to prevent the operation of the feed screw, a sleeve 80 having the 115 teeth 81 thereon is arranged to engage the end of the gear wheel 62 in a counter clockwise direction, viewing Figs. 3 and 4, and permits the operation of the screw 34 by the motor only when the latter rotates in a 120 clockwise direction as the end 82 of the plate 83 will ride over the projections 81 when the gear wheel 67 is driven in the proper direction. The gear wheel 62, however, is prevented from rotating in the opposite direction, since the end 82 of the plate 83 will engage the teeth 81 and lock the same against rotation.

The two upright supports 71 and 72 are rigidly secured to the base 10 intermediate 130

- its ends and at opposite sides thereof and at their upper ends are connected to a curved holder 73 to which the reflector 74 is rigidly attached. The vertically disposed reflector 74 may be of any suitable design for projecting the rays of light from the arc formed by the electrodes 22 and 35, and is provided with an opening 75 at its center through which the electrode 35 extends.
- 10 The reflector 74 being permanently secured in position has a fixed focus, and in order to bring the arc to the proper point for a maximum reflection of the light the entire arc mechanism including the carbon standards on which the electrodes are mounted, the feed screw, the motor and its connection to operate the feed screw 33, are slidably adjustable, as the frame comprising the yokes 16 and 17 and rods 20 and 21 is longitudinally adjustable on the rods 14 and 15 for a short distance.
- 15 Positive and negative terminal plates 85 and 86 are permanently secured to the base 10 near one longitudinal edge thereof, and each is provided with a tapering edge 87 to engage beneath a spring terminal contact permanently mounted on the casing within which the arc apparatus is located when mounted on a locomotive or other vehicle.
- 20 Handles 88 at the opposite edge are provided to slide the arc lamp into and out of the casing, ledges 89 along the edge of the base fitting suitable corresponding grooves in the casing.
- 25 A wire 90 connects the positive terminal block 85 with the positive electrode 22, and a wire 91 connects the positive terminal 85 with the shunt field coil 98 of the motor M. The brush 93 of the motor M is connected to one terminal of the motor field coil 96, by a wire 99, the other terminal of said coil being connected to the bipolar starting magnet 42, 43, by a wire 97. The negative electrode 35 is also connected to the common terminal screw 411 of the bipolar starting magnet by the standard 39 or in the diagram by the conductor 95. The brush 92 of the motor M is connected by the conductor 100 to the negative terminal block 86.
- 30 When the circuit is open, the ends of the two electrodes are in contact. On closing the circuit the magnet comprising the coils 42 and 43 is energized, and the armature 40 to which the negative electrode holder 36 is attached is drawn so as to strike an arc between the electrodes 22 and 35. As the electrodes are consumed, the voltage and resistance of the arc gap increases, causing more current to flow through the field coil 98 which is wound of fine high resistance wire. An increased current will also flow through the armature of the motor M. The field coil 96 is of heavier wire and of less resistance, and the field set up by the same normally opposes and balances the field set up
- 35 by the field coil 98 so that the motor armature M will remain stationary when the arc electrodes are at the proper working distance or when the voltage at the arc is at a predetermined value. The balanced condition of the field coils 96 and 98 is arranged by the proper adjustment of the resistances of the armature and field coils 96 and 98. When the voltage of the arc rises up above a predetermined value or when the electrodes 22 and 35 separate to a greater extent, owing to the wearing away of the same, more current will traverse the high resistance coil 98 and motor armature M and cause an unbalanced resulting field which 40 will effect the rotation of the motor armature and the operation of the feed screw 34 which feeds the electrodes toward one another the proper amount to effect a readjustment to the predetermined arc voltage 45 and gap. The rotation of the gear wheel 62 with its eccentric 61 effects a reciprocation of the connecting rod 59, causing the pawl 58 to engage the ratchet teeth 57 and thereby rotating the screw shaft 34 which is 50 mounted to rotate with the disk 55. The gear wheel 62 and the parts with which it is connected are prevented from rotating in a clockwise direction by the end 82 of the stop plate 83 which is adapted to engage 55 teeth 81 rigidly connected with the gear wheel 62; consequently, the electrodes are moved only in one direction by the motor M.
- 55 It will thus be understood that if the electrodes are separated to an undesirably great extent the shunt field becomes abnormally excited and the motor will start and attain a speed of four thousand to six thousand R. P. M. feeding the carbons toward each other until the resistance of the arc is sufficiently reduced to permit the series field to become abnormally excited. Then the series field overpowers the shunt field and the motor is stopped instantly, the fields operating in this respect as a magnetic brake. In 60 order that the reversed motor shall not continue to feed the electrodes the stop devices illustrated in detail in Fig. 4 are provided. The motor will then stop instantaneously but might otherwise reverse and bring electrode points together tightly as the voltage increases and decreases with a variation of the distance between the electrodes. The magnetic braking action of the motor is an important feature of the operation of the 65 regulating mechanism.
- 70 When it is desired to separate the electrodes 22 and 35 for any reason the pawl 58 is lifted from engagement with the toothed edge of the wheel 55 and thrown back so that the free end thereof will rest on the rod 59, a pin 583 extending through the pawl near its free end for a sufficient distance so that it will engage the rod 59 and suitably support the pawl. The toothed 75

wheel 59 may then be rotated in the reverse direction, a handle 551 being provided on the outer face thereof for this purpose. By rotating the toothed wheel 55 in a counter clockwise direction, the feed screw 34 is turned so as to cause the simultaneous movement and separation of the standards 25 and 39 and the carbons 22 and 35, respectively. Even when the electrodes are in this position and the current is turned on, the motor M will immediately operate the feeding mechanism so that the electrodes will advance toward each other and serve to maintain the electrodes at the proper distance apart. The motor might be termed a normally inactive and automatic differential magnetic brake motor.

The operation of the mechanism will be clear from the foregoing description. The 20 slideable frame on which the horizontally disposed electrodes, motor and feeding mechanism are mounted may be moved horizontally so as to set the arc at the proper point for a maximum reflection by the reflector 25 74 which latter is permanently mounted in an upright position intermediate the ends of the base or support 10. A small central opening 75 in the reflector 74 is the only portion of the reflector which is incapable 30 of reflecting the rays from the crater in the electrode 22. The standard 25 and electrode 22 obstruct very little of the light reflected, which is a great advantage in the apparatus of this invention. The entire apparatus being carried on a suitable base 10 serves to permit the removal in entirety of the arc mechanism from the interior of the casing in which it is carried when it is necessary to make repairs or adjustments.

40 It will be seen that I have provided a simple and efficient mechanism which automatically maintains the voltage between the arc points at a predetermined value, thus giving a steady light of constant candle power. As it is apparent that numerous changes may be made in the details of the apparatus without departing from the spirit of the invention, I do not wish to be limited to the exact details, as shown and 45 described.

Having thus fully described my invention, what I claim is:

1. In an electric arc lamp, the combination of two relatively movable electrodes, a screw shaft adapted to effect relative movement between the electrodes, a normally inactive reversible electric motor included in a circuit with the electrodes and adapted to rotate said shaft, said motor being automatically rendered active to turn in one direction and rotate said shaft when the electrodes are separated a predetermined distance and the direction of rotation of the motor being automatically reversed when 65 the electrodes are restored to proper rela-

tion, and means for checking such reverse movement prior to its actuating the shaft.

2. In an electric arc lamp, the combination of two relatively movable electrodes, a screw shaft adapted to effect relative movement between the electrodes, a normally inactive reversible electric motor included in a circuit with the electrodes, a wheel geared to the motor and adapted to turn the shaft, the motor being automatically rendered active to turn in one direction and rotate the shaft when the electrodes are separated a predetermined distance and the direction of rotation of the motor being automatically reversed when the electrodes are restored to normal relation, and a stop extending into the path of teeth turning with said wheel to prevent rotation thereof in one direction, whereby the shaft will not be actuated when the motor is reversed. 85

3. In an electric arc lamp, the combination of two relatively movable electrodes, a screw adapted to effect relative movement between the electrodes, a ratchet wheel secured to the shaft, a normally inactive reversible electric motor included in a circuit with the electrodes, a pawl coöperating with the ratchet wheel and adapted to be reciprocated by the motor, the latter being rendered active to turn in one direction when the electrodes are separated a predetermined distance and the direction of rotation of the motor being automatically reversed when the electrodes are restored to proper relation, and a stop device adapted to prevent such reverse movement from effecting an actuation of the pawl sufficient to turn the ratchet wheel. 90

4. In an arc lamp, the combination of horizontally arranged electrodes, independently movable standards for supporting said electrodes, a feed screw for moving said electrodes toward each other, and means for rotating said feed screw comprising a toothed wheel rotatable therewith, an electric motor normally inactive but adapted to be rendered active to rotate its armature and the shaft thereof when the voltage across the arc between the electrodes increases above a predetermined value, and means including gearing between the motor armature shaft and said toothed wheel for operating said feed screw. 105

5. In an arc lamp, the combination of two electrode holders, electrodes carried by said holders, means for separating said electrodes to strike an arc between them, means for feeding said electrodes toward one another, said means comprising an electric motor having a differentially wound field adapted to rotate the armature of the motor when the voltage between said electrodes reaches a predetermined value, a ratchet wheel rotatable in one direction only, a reciprocating member for actuating said ratchet wheel, a 110 120 125 130

device rotatable by said motor armature and adapted to reciprocate said member, and means to prevent said motor from rotating said device in one direction, whereby said reciprocating member is only actuated when said differentially wound field becomes unbalanced in one direction.

In testimony whereof I affix my signature in presence of two witnesses.
